Primary Examiner — Katie Jane Stofko*(74) Attorney, Agent, or Firm* — Bereskin & Parr LLP/S.E.N.C.R.L., s.r.l.(57) **CLAIM**

The ornamental design for a cupcake with contrasting icing, as shown and described.

DESCRIPTION

FIG. 1 is a perspective view of a cupcake with contrasting icing;

FIG. 2 is a front view of the cupcake with contrasting icing of FIG. 1;

FIG. 3 is a rear view of the cupcake with contrasting icing of FIG. 1;

FIG. 4 is a right side view of the cupcake with contrasting icing of FIG. 1;

FIG. 5 is a left side view of the cupcake with contrasting icing of FIG. 1;

FIG. 6 is a top view of the cupcake with contrasting icing of FIG. 1; and,

FIG. 7 is a bottom view of the cupcake with contrasting icing of FIG. 1.

The broken lines shown in FIGS. 1-7 illustrate portions of the cupcake with contrasting icing, that form no part of the claimed design.

The drawings include contrasting tones which represent surface ornamentation.
